UNITED STATES PATENT OFFICE

112,370

DESIGN FOR AN AUTOMOBILE EXHAUST SHROUD

Louis A. Koch, Louisville, Ky.

Application September 23, 1938, Serial No. 80,065

Term of patent 14 years

To all whom it may concern:

Be it known that I, Louis A. Koch, a citizen of the United States, residing at Louisville, in the county of Jefferson and State of Kentucky, have invented a new, original, and ornamental Design for an Automobile Exhaust Shroud, of which the following is a specification, reference being had to the accompanying drawings, forming a part thereof.

In said drawings:

Figures 2, 3 and 4, respectively, are top plan, side elevation, and bottom-plan views thereof; and

I claim:

The ornamental design for an automobile exhaust shroud, as shown.

LOUIS A. KOCH.
